[57] CLAIM

The ornamental design for a magnetic separator for particulate materials, as shown and described.

DESCRIPTION

FIG. 1 is a front elevational view of a magnetic separator for particulate materials showing our new design; FIG. 2 is an elevational view from one side; FIG. 3 is an elevational view from the other side; FIG. 4 is a back elevational view; and FIG. 5 is a top plan view.

FIG. 1.

FIG. 2

FIG. 3

FIG. 4.

FIG. 5.
